UNITED STATES PATENT OFFICE

101,668

DESIGN FOR A CASE FOR RADIO RECEIVING APPARATUS

Walter A. Frantz, Shaker Heights, Ohio

Application June 21, 1934, Serial No. 52,267

Term of patent 14 years

To all whom it may concern:

Be it known that I, Walter A. Frantz, a citizen of the United States of America, and a resident of Shaker Heights, in the county of Cuyahoga and State of Ohio, have invented a new, original, and ornamental Design for Case for Radio Receiving Apparatus, of which the following is a specification, reference being had to the accompanying drawing, forming part thereof.

In the drawing, the figure is a perspective view

of a case for radio receiving apparatus showing my design.

The rear of the case is plain and the opposite sides of the case are substantially identical in appearance.

I claim:

The ornamental design for a case for radio receiving apparatus as shown and described.

WALTER A. FRANTZ.
